A. McLAIN

TOOL FOR BENDING PIPE, BARS, AND THE LIKE

Filed Dec. 5, 1924

FIG. 1

FIG. 2

FIG. 3

INVENTOR

Andrew McLain
By Kay, Totten & Martin
Attorneys.

UNITED STATES PATENT OFFICE.

ANDREW McLAIN, OF CARNEGIE, PENNSYLVANIA.

TOOL FOR BENDING PIPE, BARS, AND THE LIKE.

Application filed December 5, 1924. Serial No. 754,145.

To all whom it may concern:

Be it known that I, ANDREW McLAIN, a citizen of the United States, and resident of Carnegie, in the county of Allegheny and State of Pennsylvania, have invented a new and useful Improvement in Tools for Bending Pipe, Bars, and the like; and I do hereby declare the following to be a full, clear, and exact description thereof.

10 My invention relates to bending tools, and particularly to a tool suitable for bending pipe and the like.

One object of my invention is to provide a tool whereby the smaller sizes of pipe 15 may be conveniently bent manually and in bends of varying degrees.

Still another object of my invention is to simplify and improve generally the structure and operation of bending tools.

20 One form which my invention may take is shown in the accompanying drawing wherein Fig. 1 is a view, in side elevation, of a tool embodying my invention, with a piece of pipe in position therein; Fig. 2 is an end elevational view of the device of Fig. 1, and Fig. 3 is a sectional view showing the positions assumed by the parts of the tool during a bending operation.

The tool consists of a handle 4 of suitable length bifurcated at its lower end and provided with perforations for the reception of bolts 5 and 6 that serve as pivots for the bending dies.

35 The bending dies consist of a normally stationary die member 7 which is pivotally supported from the bolt 5, and a movable die member 8 that is pivotally supported by the bolt 6. The movable die member is provided with a series of perforations preferably arranged on an arcuate line as shown, to provide for adjustability as between it and its fulcrum 6 that is carried by the handle 4.

40 The dies 7 and 8 are beveled or curved as indicated at the points 9 and 10, respectively, to eliminate corners which would otherwise bite into or mar the pipe. This is particularly advantageous in the case of the die member 8, because it ordinarily 45 slides along the pipe somewhat during a bending operation.

In the operation of my device, the bending tool is placed in position upon a pipe 11, and the bolt 6 placed in that hole of the die 8 which will result in securing a 50 bend of the desired curvature when the

handle is operated as hereinafter described. Furthermore, the adjustment provided as between the die 8 and the bolt 6 permits the tool to be employed in connection with 60 pipes or rods of relatively small diameter, as well as with those whose diameters are substantially equal to the openings through the dies.

When the parts have been arranged as 65 shown in Fig. 1, the handle is moved to the right, causing the die 8 to fulcrum upon the upper end of the die 7 and the bottom portion thereof to engage the underside of the pipe and draw the outer end 70 thereof upward as shown in Fig. 3, the lower end of the die 8 meantime sliding longitudinally of the pipe 11.

Upon completion of the bending operation 75 the tool may be slid from the pipe, ready for use in connection with another pipe.

From the foregoing it will be seen that I provide a tool that may be conveniently carried by electricians, plumbers, pipe fitters and the like, and employed in bending pipe and conduit at the place of installation, and that the tool is capable of placing a comparatively smooth bend in pipe and of substantially any desired angle. 85

It will of course be understood that various changes in detail and general arrangement may be made without departing from the spirit and scope of the invention as defined in the accompanying claims. 90

I claim as my invention:

1. A bending tool comprising a handle, a fixed die member, a second die member movable with the handle, said die members adapted to engage a pipe, and means for 95 causing the movable die member to move in an arcuate path of decreasing radius, upon movement of the handle.

2. A bending tool comprising a handle, a fixed die member normally vertically disposed, and a movable die member fulcruming on the upper end of the stationary die member and pivotally connected to the handle at a point above the fulcrum point of said movable die. 100

3. A bending tool comprising a handle, a stationary die pivotally connected to one extremity of said handle, a movable die member, an arcuate extension on said movable die member, means for pivotally connecting the said extension to said handle, and a fulcrum for the movable die member. 110

disposed eccentrically of the pivot for said extension.

4. A bending tool comprising a handle, a stationary die pivotally connected to one extremity of said handle, a movable die member, an arcuate extension on said movable die member, means for adjustably and pivotally connecting the said extension to said handle, and a fulcrum for the movable die member disposed eccentrically of the pivot for said extension.

5. A bending tool comprising a handle, a stationary die pivotally connected to the lower end of said handle, a movable die member, an arcuate extension on said die

member, and means for pivotally connecting the said extension to said handle, the said extension being so disposed as to fulcrum upon the upper end of the stationary die member.

6. Bending apparatus for cylindrical objects, comprising means for holding an object to be bent, and a die member for engaging said object and movable longitudinally thereof, in an arcuate path of gradually decreasing radius.

In testimony whereof I, the said ANDREW McLAIN, have hereunto set my hand.

ANDREW McLAIN.
